UNITED STATES PATENT OFFICE.

HENRY F. PARKER, OF NEW YORK, N. Y., ASSIGNOR TO HALLECK A. PENROSE, OF NEW LONDON, CONNECTICUT.

DESIGN FOR A FLYING TARGET.

SPECIFICATION forming part of Design No. 23,027, dated January 30, 1894.

Application filed March 24, 1893. Serial No. 467,507. Term of patent 14 years.

To all whom it may concern:

Be it known that I, HENRY F. PARKER, a citizen of the United States, residing at the city, county, and State of New York, have invented and produced a new and original Design for Flying Targets, of which the following is a specification, reference being had to the accompanying drawings, forming part thereof.

10 Figure 1, is a face view of the target showing the design; and Fig. 2, a cross-sectional view taken on the line $x-x$, Fig. 1; these two views being deemed necessary to fully illustrate the design.

15 The design applies to a saucer shaped target of brittle composition for trap shooting.

The leading feature of the design consists in a series of corrugated embossments radiating from the center of the target, which bears 20 the figure E, of a pigeon or other bird's head; and the said embossments are arranged to resemble the feathers of a bird. The corrugated embossments radiate spirally, as shown,

and are arranged in different series. The inner series A, at the depressed center of the target resemble in general effect, the neck, and body feathers of a bird. The intermediate series B, at the crown of the target and the outer series C, resemble wing feathers in general effect, overlapping one another, 30 and the intermediate series B, have their raised surfaces partially flattened. The intersections of the corrugations C, with the flat shoulder D, of the rim of the target, produce a scalloped outline, which together with the 35 scalloped outline of the series B, set out the corrugated character of the design in an effective manner.

What I claim is—

The design for a flying target substantially 40 as shown and described.

HENRY F. PARKER.
